UNITED STATES PATENT OFFICE.

HAROLD EDWARD NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR AN ARTICLE OF HOLLOW WARE.

52,830.

Specification for Design. Patented Dec. 31, 1918.

Application filed May 13, 1918. Serial No. 234,332. Term of patent 7 years.

To all whom it may concern:

Be it known that I, HAROLD EDWARD NOCK, a citizen of the United States, residing at Newburyport, in the county of Essex and State of Massachusetts, have invented a new, original, and ornamental Design for an Article of Hollow Ware, of which the following is a specification, reference being had to the accompanying drawing, forming a part thereof.

In the accompanying drawing Figure 1 is a view in side elevation, Fig. 2 is a view in front elevation and Fig. 3 is a top plan view of the novel design shown applied to a coffee-pot.

The design comprises an article of hollow ware having the configuration delineated and, as shown, is embodied in a coffee-pot, but it is contemplated that the design may be embodied in or applied to tea-pots, sugar or waste bowls, cream or water pitchers, gravy boats, and other analogous articles of hollow ware. It will be understood that the particular shape of the handle, spout and cover is not novel.

I claim:

The ornamental design for an article of hollow ware as shown and described.

HAROLD EDWARD NOCK.
